UNITED STATES PATENT OFFICE.

GUY E. SWARTZ, OF DETROIT, MICHIGAN.

DRILL BUSHING.

Application filed December 16, 1925. Serial No. 75,688.

In the drilling of metals considerable trouble is often experienced from the formation of long chips or cuttings which it is often necessary to remove manually and which often results in the hands of the operator being cut, although this danger is sometimes avoided by the use of a hook. In any case the necessity for such removal of the chips presents an inconvenience and in many cases slows up the work, as they have a tendency to wind upward on the drill and their frequent removal occupies a certain amount of time and distracts the operator's attention from the work.

Where drill jigs are employed it is usual to employ a bushing for the guidance of the drill, and the presence of unbroken chips or cuttings winding upwardly on the drill frequently necessitates removing the bushing or allowing it to lift out of the fixture in order to prevent the chips clogging thereunder as would otherwise occur, and such removing or lifting of the bushing is also liable to result in inaccurate drilling particularly when the lifting is effected by the pressure of the chips therebeneath so that the bushing floats out of position and its usefulness as a guide is lost for the time being.

Still further, time is frequently lost by the necessity of clearing the drill of long chips which are curled thereon before the bushing can be placed in position for the drilling of a succeeding hole.

This invention therefore has for its object to provide a form of bushing which by its use will eliminate the disadvantages hereinbefore referred to, and which may be permanently placed in a jig fixture due to the fact that there is no necessity of removing or lifting it from the fixture for the purposes related.

A further object is to provide a bushing for use in drilling operations wherein special means are provided for the breaking of the cuttings, resulting from a drilling operation, into short lengths whereby they will fall downward instead of winding upwardly on the drill; and still further objects subsidiary to or resulting from the aforesaid objects, or from the construction or operation of the invention as it may be carried into effect, will become apparent as the said invention is hereinafter further disclosed.

In carrying the said invention into effect, I may provide a bushing of brass or other suitable material adapted to act as a guide

for a drill, the said bushing being provided with a downwardly opening conical or flared mouth and with upwardly extending grooves in the wall of the bore thereof, the said grooves being widened at their lower ends to receive the extremities of chips or cuttings travelling upwardly on the drill whereby the spiral progress of the said cuttings is interrupted and they tend to travel upwardly through the said grooves, with the result that, as the drill revolves, the said cuttings are broken into small pieces and fall from the mouth of the said bushing on to the work or work table.

All of which is more particularly described and ascertained hereinafter, by way of example, having reference to the accompanying drawing, wherein—

Figure 1 is an elevation partly in section of a drill jig, illustrating the lower end of a drill and work in position, the said drill being guided by a bushing embodying the said invention;

Figure 2 is a section taken on the line 2^x—2^x, Figure 1; and

Figure 3 is a detail sectional elevation of the bushing removed.

Similar characters of reference indicate similar parts in the several figures of the drawing.

1 indicates a drill jig fixture supporting a piece of work 2, and 3 a drill operating upon the said work, the said fixture being bored at 4 for the reception of a bushing 5, the said bushing acting as a guide for the said drill in the manner well known.

Ordinarily plain bushings are employed in this capacity, and the chips formed by and extending upwardly around the drill result in the disadvantages hereinbefore referred to.

It will be seen that the present bushing is provided at its lower end with a conical or flared mouth 6 for the interruption and reception of chips or cuttings which curl upwardly around the drill, and that the inner wall of the said bushing is provided with upwardly extending grooves 7, the lower ends of which are widened as at 8 to provide approaches therefor. Thus when the ends of cuttings travelling upwardly around the drill strike the conical mouth of the said bushing they will in the course of their motion eventually enter the widened lower ends of the said grooves 7, and as their motion is a rotary one, this

motion will be interrupted by the tendency of the cuttings to travel upwardly through the grooves and the interruption of their rotary motion by the sides of the grooves and consequently the cuttings will be broken up into short lengths. These short lengths being no longer supported will then fall downwardly around the drill and are easily disposed of without danger or loss of time, and the upper part of the drill is therefore kept free of such cuttings.

Incidentally, no clogging of the chips beneath the bushing will take place, as is possible with the ordinary plain bushing, and as no necessity for the lifting or removal of the bushing to relieve such chips or cuttings exists, the bushing may be firmly fixed in the said jig fixture so that no adjustments thereof will be required, and it will always be maintained in correct relation to the work.

It is preferred that the lower end or mouth of the bushing shall be arranged in spaced relation to the work in order to give sufficient clearance for the free discharge of the chips therefrom.

Although very simple in construction and operation, the described device successfully overcomes all of the disadvantages previously pointed out which are met with in the use of plain bushings, and by its use the drilling of work in jig fixtures is greatly facilitated.

The grooves 7 are shown as extending completely through the bushings 5 because this is a satisfactory form for machining by ordinary methods, but it is not essential that the grooves so extend completely through the bushing as it is the lower ends or mouths of the grooves which form the abutments resulting in the breaking of the chips in the manner described. Consequently term "groove", as used herein, is

intended to refer to any form or slot, notch or recess in the mouth of the bushing which will serve as a means of interrupting the drill chips at the mouth of the bushing and breaking them between the mouth of the bushing and the work.

This invention may be developed within the scope of the following claims, without departing from the essential features of the said invention, and it is desired that the specification and drawing be read as merely illustrative and not in a limiting sense, except as necessitated by the prior art.

What I claim is:—

1. A self cleaning guide for metal working drills comprising a bushing bored for the passage of a drill therethrough, said bushing having a flared mouth at its lower end, and upwardly extending grooves in the inner wall thereof from said flared mouth, said grooves being adapted to interrupt cuttings extending upwardly around the drill whereby such cuttings are broken into small pieces.

2. A device according to claim 1, wherein the grooves are widened at their ends adjacent the mouth of said bushing.

3. In combination with a device for the guidance of a metal working drill relative to work, a self cleaning drill guide fixed in said device, said guide comprising a fixed bushing having a flared mouth in spaced relation to the work and provided with grooves extending upwardly in the inner wall of said bushing from said flared mouth for the interruption of cuttings entering the mouth of said bushing, whereby such cuttings are broken up between the mouth of the bushing and the work.

In testimony whereof I affix my signature.

GUY E. SWARTZ.
